UNITED STATES PATENT OFFICE

LEWIS C. BROECKER, OF BRIDGEPORT, CONNECTICUT, ASSIGNOR TO BRIDGEPORT BRASS COMPANY, OF BRIDGEPORT, CONNECTICUT, A CORPORATION OF CONNECTICUT

DESIGN FOR A SEAL CAP ADAPTED FOR VALVE STEMS

Application filed June 16, 1931. Serial No. 40,230. Term of patent 14 years.

To all whom it may concern:

Be it known that I, LEWIS C. BROECKER, a citizen of the United States, residing at 2898 Main Street, Bridgeport, county of Fairfield, and State of Connecticut, have invented a new, original, and ornamental Design for Seal Cap Adapted for Valve Stems, of which the following is a specification, reference being had to the accompanying drawings, forming part hereof.

In the drawings—

Figure 1 represents a top plan view of a seal cap embodying my invention;

Figure 2 is a side elevation thereof.

I claim:

The ornamental design for a seal cap adapted for valve stems substantially as shown.

LEWIS C. BROECKER.
